COMBINATION OYSTER ROASTER AND GRILL

Charles R. Adams, 255 Kensington Road, and Otis R. Burbage, Jr., 1790 Balfoure Drive, both of Charleston, S.C. 29407; and Linwood W. Stancil, Jr., Charleston, S.C. (4748 Bordwell Drive, San Jose, Calif. 95118)

Filed Sept. 22, 1967, Ser. No. 8,692

Term of patent 14 years

Int. Cl. D7—04

U.S. Cl. D81—10

Fig. 1.

Fig. 2.

FIGURE 1 is a front perspective view of a combination oyster roaster and grill embodying our new design; and FIGURE 2 is a perspective view of the combination oyster roaster and grill, taken from the rear of FIGURE 1, further illustrating our new design.

We claim:

The ornamental design for a combination oyster roaster and grill, substantially as shown.
